UNITED STATES PATENT OFFICE.

ERNEST HOWARD FARMER, OF LONDON, ENGLAND.

APPARATUS FOR THE PRODUCTION OF PHOTOGRAPHIC NEGATIVES.

1,231,581.

Specification of Letters Patent.

Patented July 3, 1917.

Application filed October 18, 1916. Serial No. 126,235.

To all whom it may concern:

Be it known that I, ERNEST HOWARD FARMER, a subject of the King of Great Britain, residing at London, in the county 5 of Middlesex, England, have invented certain new and useful Improvements in Apparatus for the Production of Photographic Negatives; and I do hereby declare the following to be a full, clear, and exact description of the invention, such as will enable others skilled in the art to which it appertains to make and use the same.

My invention consists in the novel features hereinafter described, reference being 15 had to the accompanying drawings which illustrate my improved method and several forms of apparatus for carrying the same into effect, and the said invention is fully disclosed in the following description and 20 claims.

The object of my invention is to inclose a photographic plate cut film or paper, or other material, provided with sensitized surface, within a light proof container, so that 25 it may be exposed to the action of light for the purpose of producing a photographic image without the prior need of a dark room and further developing and fixing the photograph without removing it from the container 30 whereby the subsequent use of a dark room is also rendered unnecessary, while at the same time the plates, films or papers are at all times protected from injury from light, dust, dampness, injurious vapors, and 35 finger marks.

My improved process and apparatus enables one to make photographic exposures and immediately develop in day light, in the field, or elsewhere away from the conveniences of civilization, if necessary, so as to 40 immediately produce the finished negatives and will be found particularly desirable in educational work in the teaching of photographic work, and the performance of such 45 work under the guidance of instructors, and also for the purpose of obtaining the immediate development of plates, films, or papers exposed by operators on vacation when away from home, on camping expeditions, and 50 search expeditions; and the like.

According to one form of my invention, I provide a simple container of non-actinic material preferably comprising two sepa-

rable members which, when in closed position, are provided with portions sufficiently 55 over-lapping or engaging each other with sufficient contact of surfaces having changes of direction so as to form light traps and prevent the access of light into the interior. One or more sensitive plates are secured 60 by their edges or unsensitized surfaces within the casing to the separable members thereof, and when closed and properly secured the container forms a light proof packing in which the sensitized plates may be prepared 65 and sold by manufacturers, or into which they may be placed from the manufacturer's package and from which they need not be removed until they are completely developed and fixed so as to be unaffected by 70 actinic light.

The said containers are adapted to be inserted in suitable holders, or directly in the cameras, exposure of the sensitive surfaces being made by opening the container 75 after it is placed in operative relation with the camera, the container being closed before being removed from operative relation therewith, and the container is provided with means whereby developing, fixing, and 80 other solutions can be introduced into the interior in contact with the sensitive surfaces, as for example, by providing a hole or holes at one end masked or closed temporarily as by non-actinic paper which may 85 be punctured for the purpose of admitting the developing and other liquids.

The casing members are provided with means for enabling them to be engaged by suitable retaining and actuating mechanism 90 so that the separable members may be separated temporarily when in operative relation with the camera to make the desired exposure of a sensitive surface.

My invention also contemplates other features and objects which will be more fully explained hereinafter.

For convenience of reference I will use the term "plate" hereinafter, in the specification and in the claims, as meaning the 100 sensitive coating and the material supporting the same whether it be glass, celluloid, paper, or other material.

Referring to the accompanying drawing:

Figure 1 represents a sectional view of a 105 photographic camera with which my im-

proved container can be conveniently employed showing one of the containers in place preparatory to separating the members of the container and exposing one of the plates carried therein.

Fig. 2 is an enlarged perspective view partly in section showing a convenient arrangement for retaining one member of the container in position while the other member is raised to separate the members and affect the exposure of one of the plates carried thereby.

Fig. 3 is a sectional view illustrating a double flap holder which is a pattern suitable for carrying out my method; together with an inclosed container carrying two plates.

Fig. 4 is a similar view of the container detached.

Fig. 5 is a similar view of a modified form of container which may be employed to accommodate four photographic plates.

Fig. 6 is a similar view of another modification of the container adapted, in this instance, to carry two photographic plates and being provided with a central light proof shield or partition between the opposed sensitive surfaces for protecting one of the same while the other is being exposed in the camera.

Fig. 7 is a similar view of another modification of the container.

Fig. 8 represents a double flap plate holder provided with removable slides and capable of use in cameras operating with plate holders, the said holder being arranged to hold one of my improved containers, and expose the plates carried thereby.

Fig. 9 is a perspective view of the plate holder with one slide removed.

Fig. 10 represents one of the containers, and illustrates one means for introducing the developing and fixing solutions into the same.

Fig. 11 represents a sectional view of a developing tank showing one of my improved containers inserted therein and illustrates one means of admitting the developing solution or other solution to the interior of the container.

Fig. 12 is a section showing another form of developing tank and one of my improved containers immersed therein, and illustrates the method of introducing the liquid in the tank to the interior of the container.

Fig. 13 is a sectional view of another form of camera with which my improved container may be advantageously employed.

Fig. 14 is a view similar to Fig. 1 showing a movable shield attached to the interior of the camera and adapted to be moved into horizontal position to protect the plate or plates not intended to be exposed.

Fig. 15 represents a section on line 15—15 of Fig. 14.

Fig. 16 is a view similar to Fig. 1 showing one means for retaining the partition member of my improved container in horizontal position during exposure.

Fig. 17 is a detail view partly in section showing a portion of the container, the partition member having a part extending rearwardly outside of the container and the retaining block for holding the partition member in horizontal position as indicated in Fig. 16.

Fig. 18 is a view similar to Fig. 1 showing another means for retaining the partition in horizontal position.

Fig. 19 is a detail view showing a portion of the camera illustrated in Fig. 13 and the lens tube therefor, said lens tube being movable to two focal positions.

In its simplest form illustrated, for example, in Fig. 4, my improved container comprises a casing which may be of cardboard or any other suitable non-actinic material, preferably formed in two parts or members indicated at 1 and 2, and having its edges provided with means for forming a light trap such as overlapping portions, 3 and 4, the portions 3 being attached to the member, 1, in Fig. 4 and overlapping the portion, 4, which is attached to the member, 2, very much after the manner of the manufacture of paper boxes and covers therefor.

5 and 6 represent two photographic plates having sensitized material, 7, on their inner faces and these plates are secured in any desired way to the members, 1 and 2, of the container, for example, by means of suitable adhesive applied to the non-sensitized faces, or in any other desired way, which will hold them in fixed relation with the members to which they are attached until after the developing and fixing operations.

In Fig. 4 I have shown at one end of the container an aperture, 8, for the admission of the developing and fixing solutions as hereinafter described, which aperture is normally temporarily closed in any desired way as by a strip, 9, of non-actinic paper or other material.

For convenience in handling the containers the separable members thereof may be temporarily united and sealed together as by means of a strip or tape of paper or other material indicated at 10 extending around the edges of the container and adhesively applied thereto which can be readily broken by the finger nail or a sharp instrument when the container is ready to be placed in operative relation with a camera, but the separable members may be temporarily retained in closed position by any other suitable means.

In order to expose one of the sensitive surfaces, it is only necessary to place the container within the camera or other light proof receptacle within the focus of a suitable lens

and separate the members of the casing so as to bring one or other of the plates into the focal plane of the lens. Obviously if the container is placed in a horizontal position 5 within the camera the uppermost plate can be exposed by raising the upper member of the container, and the lower plate can be exposed by reversing the position of the container and raising the member with 10 which the other plate is connected. If the container is placed in the camera in a vertical position, one plate can be exposed by lowering one of the separable members into horizontal position while retaining the other 15 in vertical position, and the other plate can be exposed by reversing the position of the container while it is in closed position and replacing it within the camera. Suitable means are provided according to the circumstances of use for retaining one member of the container in fixed relation with the camera while the other member is provided with means to enable it to be acted upon by suitable actuating means for effecting the 20 separation of the two members.

For example, in Figs. 1 and 2 the members of the container are shown as provided on their edges with strips, 11, forming a groove or recess between the same to engage 25 horizontal ribs, 12, provided on the interior of the lateral portions of the camera body, and the camera here indicated at 13 is provided with a removable back, 14, or closure to afford access to the interior for the placing 30 of the container within the same. The two members of the container are preferably hinged together at one end to facilitate the opening and closing thereof, and where a tape, 10, for example, is applied all the way 35 around the container it may be broken only on three sides so as to provide a hinge on the fourth side, or a special hinge of cloth or paper may be applied to the container members.

45 The opposite end of the container will be provided with suitable means for permitting it to be acted upon by an actuating device. A simple form of this is illustrated in Fig. 4 and in Figs. 1 and 50 2 in which the container is provided on its upper and lower faces with a strap or straps, 15, of paper or other suitable material to receive a tongue, 16, carrying an eye, 17, which is engaged by a hook on the end of a draw 55 rod, 18, which, in this instance, extends through a sleeve, 19, located within an opening in the upper part of the camera and held therein by an elastic fabric, 20, so as to make it light proof, and at the same time 60 accommodate the changes of position of the draw rod, which may be a stiff wire for example. The camera will, of course, be provided with a suitable lens indicated at 21. To effect an exposure under these conditions 65 the container is placed in position in the

body of the camera so that the lower member is held in place by the ribs, 12, and the draw rod, 18, and slide, 16, are connected with the upper member as shown in Figs. 1 and 2. The back of the camera is then 70 closed and the rod, 18, is drawn upward so as to bring the upper member of the container into vertical position, and the plate carried thereby into position to receive the image when the lens is uncovered. As soon 75 as the exposure is made the draw rod will be operated to again close the container which can then be safely removed from the camera turned upside down and replaced with the draw rod connected with the other 80 member of the container when the second sensitive surface may be in like manner exposed and the container again closed.

To develop the plates within the container it is only necessary to introduce through the 85 aperture, 8, a suitable developing solution and this may be accomplished, for example, by means of a small funnel, 22, as indicated in Fig. 10, which may be conveniently provided with a vent, 23, or obviously the container itself might be provided with a vent opening also suitably closed by a strip of black paper on the interior like the inlet opening. The development may be determined by taking the time thereof or in any 90 other suitable way and the developing liquid may be poured out and a suitable fixing solution may be inserted in the same way, after which the plates can be removed from the container and washed, or can be washed 100 while still within the container, as may be desired, and in some instances, it may be found desirable to dry the plates and pack them for shipment or transportation without taking them out of the container from which 105 it is only necessary to remove them for printing.

In Fig. 12 I have shown how the container may be conveniently used in connection with a developing tank indicated at 24 partially 110 filled with the developing or fixing solution in which case the container may be inserted in the tank with the inlet aperture, 8, at the bottom so that the developing or fixing liquid will be forced upward within the container, the air being permitted to escape around the edges of the separable members as the liquid 115 enters.

In Fig. 11 I have shown another form of developing tank adapted especially for use 120 in case the container is not provided with the apertures, 8, in which case the tank indicated at 25 is provided with a cover, 26, having a slot, 27, at one side to accommodate a small hook, 28, which may be inserted in the strap, 15, of the container, the opposite side wall of the tank being provided with a retaining device, 29, to engage the other strap on the other member of the container. After the 125 cover, 26, is placed in position the hook, 28, 130

may be drawn outward so as to open the container within the tank and admit the developing fluid thereto.

Obviously many variations may be made in the form of the container depending upon the number of plates it is to carry, and the specific form of the camera with which it is to be used, although obviously any of the forms herein shown may be used with practically any type of camera by making slight variations in the camera structure to accommodate this novel container.

In Fig. 5, for example, I have shown a form of container for holding four sensitive plates and comprising the members, 1^a and 2^a, formed substantially as before described with a partition member, 30, which, as shown, carries or may carry a plate on each face of the same. The members, 1^a and 2^a, 20 may be provided with the straps, 15^a, or equivalent devices, and the partition member if it is to carry sensitive plates, as shown, is provided with a sleeve, 31, which may be engaged by the actuating mechanism such as the wire, 18, shown in Fig. 1, for example. In using this form of container with four plates indicated at 5^a, 5^b, 6^a and 6^b, the first exposure may be effected by raising the member, 1^a, to expose the plate, 5^a, and a second exposure may be made by raising the partition member, 30, and the member, 1^a, to expose the plate, 6^a, after which the device may be reversed in the camera and two similar exposures made 35 for the plates, 6^b and 5^b, after which all of the container plates may be developed by introducing the developer to the interior on one or both sides of the partition member, as indicated, through apertures 8^a—8^a, normally closed by the protecting strips, 9^a—9^a.

If this type of container, shown in Fig. 5, is used for two plates only as 5^a and 6^b, the partition member, 30, would serve conveniently to further protect the plate which is not being exposed while the container is open within the camera, and my invention includes the use of a partition member when desirable. When the casings are not provided with partitions, a movable shield 50 attached to the interior of the camera is employed.

I have illustrated such a construction in Figs. 14 and 15, in which I have shown a shield of this character comprising in this instance a piece of wire bent into rectangular form and comprising the members 70—71—72—73 to which is attached a piece of light proof material, 74, such as paper, cloth, or thin metal. The member, 70, is 60 conveniently mounted in a groove cut in the side of the camera and is provided with an operating arm, 75, extending through an opening to the exterior, a groove and opening being covered by a strip or light proof 65 paper or other material, 76. It will be obvi-

ous that after one member of the container has been raised to vertical position, in position to expose the plate carried thereby, the operator can actuate the arm, 75, and swing the shield into horizontal position to protect the plate or plates in the other member of the container during the exposure of the vertically supported plate. The other parts shown in Figs. 14 and 15 being identical with those illustrated in Fig. 1 have 75 been indicated by the same reference numerals.

Fig. 6 shows another form of container which may be conveniently made of pasteboard, papier mâché, or metal in which the light traps are formed all the way around the meeting edges of the members, 1^b—2^b, by corrugated portions, 32, and in this form of the container I have shown it arranged to carry only two plates, 5^c—6^c, and I have also shown a central diaphragm or partition, 30^b. The members, 1^b—2^b, are provided with the straps, 15^b, or equivalent devices for enabling either to be lifted to expose the attached plate and where no plates are attached to the central partition and one of the members is raised to vertical position to expose the plate connected therewith, the partition is kept in place by projections in the fixed part of the holder or 95 camera, and I have illustrated in Figs. 16, 17 and 18, two means for retaining the partition in horizontal position when one of the members of the container is raised. In the form shown in Figs. 16 and 17, the central 100 partition indicated at 30^b is provided with a central disposed projecting portion, 30^c, which projects from the hinged end of the container. In this instance the camera is provided with a retaining block indicated 105 at 80 so arranged as to engage the under face of the projection, 30^c, when the container is placed in the camera, and when the upper member of the container is raised the engagement of the block with the projection, 30^c, will prevent the partition from being lifted, and will retain it in horizontal position, as shown. In Fig. 18 in which I 110 have shown a partition similar to that illustrated in Fig. 5 provided with an exterior sleeve, 31, I have shown the camera provided with a rock shaft, 81, carrying a hook or detent, 82, for engaging the sleeve, 31, of the partition, and holding it in horizontal position when the upper member of the 115 container is raised. The rock shaft will be provided on the exterior of the camera with a thumb button indicated at 83, in dotted lines, or other actuating means for rocking the shaft, 81, and throwing the hook, 82, into and out of operative position. One or both of the members, 1^b—2^b, may be provided with the apertures, 8^b—8^b, normally closed by protecting strips, 9^b—9^b for the introduction of the developing and other 120 125 130

fluids and the edges of said members may be temporarily secured by marginal strips of gummed paper or otherwise as previously described.

- 5 In Fig. 7 I have shown another form of container in which the light traps on the members, 1^c—2^c, which carry the plates, 5^a—6^a, are provided, the one with a marginal groove and the other with a marginal rib to fit within the same to form the light traps. In this instance, the groove is shown as formed by parallel pieces of wood or card-board, 33, and the rib by a single piece of wood or card-board, 34. The two members 15 may be held together by a paper strip gummed all the way around as indicated at 10^c, which may be partially destroyed at the time the device is to be used leaving a portion to serve as a hinge along one edge. One 20 of the members, 1^c—2^c, may also be provided with the aperture, 8^c, for the introduction of liquid, normally closed by the protecting strip, 9^c.

In order to more perfectly protect the 25 plates and for convenience in exposing the plates I preferably employ in connection with my improved container an exterior flap holder as indicated in Fig. 3, which comprises two members, 40—41, hinged together 30 at 42 and provided with means to engage the camera or actuating devices for opening the holder, for example, in this instance, the sleeves, 43—43, adapted to be used in conjunction with the elevating rod, 18, shown at 35 Fig. 1. In this instance, each of the members, 40—41, is provided with a sliding latch, 44, which can be pressed forward into engagement with the strap, 15, on the container which is substantially of the form 40 shown in Fig. 4, so that when one of the members, 40, is operated the corresponding member, 1 or 2, of the container will be carried with it for the purpose of exposing the contained plate. The container may be 45 removed from the holder and the plates developed by introducing the fluids through the aperture, 8, sealed by the strip, 9, as hereinbefore described. When this flap holder is employed the container need not be hinged. 50 In Fig. 8 I have shown one manner in which my improved container can be readily employed in connection with the type of plate holders having movable slides. In this figure, 50 represents the plate holder 55 which is of ordinary form and provided with the removable slides, 51—51, which may be protected by light valves (not shown) in a well known way. The central partition which is normally in this type of plate 60 holder is dispensed with and the interior of the holder is provided with two movable wings, 52—52, the lower ends of which are provided with extensions, 53, adapted to fit into the straps, 15, for example, of a container of the type shown in Fig. 4, which is

shown in connection therewith, so as to unite one of the wings, 52, with each of the members, 1—2, of the container. The wings, 52—52, are pivotally mounted within the plate holder by means of a spindle, 54, and a 70 sleeve, 55, surrounding the same, one of the wings being secured to the sleeve, and the other to the spindle, and the sleeve and spindle being provided with separate actuating arms, 56—57, at one end of the plate holder. 75 To insert the container it is only necessary to remove one of the slides, 51, and turn the wings outwardly so that the container may be inserted between them, and thus placed in the plate holder when the slide, 51, will be 80 restored. Obviously the plates, 5—6, may be readily exposed by withdrawing one of the slides while the plate holder is in operative relation with a camera and rocking one of the wings, 52, into horizontal position so 85 as to expose the plate on the other half of the container, and vice versa. The plates may be developed as hereinbefore described by removing the container from the holder.

In some instances as where a folding type 90 of camera is employed both members of the container may be secured to separable members of the camera so that the opening of the camera into operative position will also open the container and bring one or other 95 of the plates carried thereby into operative relation with the lens. Thus in Fig. 13 I have shown, for example, a folding camera having hinged members, 60—61, each of which when provided with a sliding latch, 100 64—64, adapted to engage the retaining device or strap, for example, 15^a, as shown, as I have illustrated in this connection the type of container shown in Fig. 5. 62 represents the lens, and 63 represents a bellows portion 105 which may be detachably connected to one of the members as at 63^a to permit the insertion and reversing of the container. If only two plates are carried by the container the opening of the camera will bring one of 110 these plates into operative relation with the lens, as the two members, 1^a—2^a, of the container are connected to the hinged members of the camera. If the central partition is used, as shown, and carries additional plates, 115 the member, 61, may be provided with an additional retaining device as the hook, 65, to engage the sleeve, 31, of the central partition, 30, when it is desired to expose one of the plates connected with the partition. If 120 plates are carried by both the members, 1^a—2^a, of the container as well as by the central partition, the lens, 62, may, for example, be given a range of movement backward and forward with respect to the camera in any 125 well known or desired manner to accommodate the change of focal distance between a plate carried on the front face of the partition, 30, and a plate carried on the inner face of the casing member. 130

For example, in Fig. 19, I have shown the lens, indicated at 62^a, mounted in a lens tube, 62^b, provided with stop lugs or collars, 62^c, and 62^d, the lens being movable longitudinally through the supporting opening in the front of the camera and the lugs or stops, 62^c—62^d, being so arranged as to arrest the tube and lens in the two proper focal positions. For example, when the lens tube is drawn out until stopped by the lugs or collar, 62^d, it will be in proper focal relation with a plate supported on a central partition and when the lens tube is pushed in until arrested by the stop lugs or collar, 62^c, it will be in proper focal relation with a plate supported on the inner face of the upper member of the container.

I do not desire to limit myself to the exact details of construction herein shown, and described, as my invention is capable of very wide application with practically all varieties of photographic apparatus. The advantages of being able to purchase photographic plates, (films or papers) in a container which is light proof and in which they may remain while one or more of the various steps of exposure, development and fixation can be carried out in rapid succession so as to produce when desired a finished negative within a few moments after exposure, without the use of a dark room, will be so apparent to those skilled in the art that they need not be enlarged upon herein.

What I claim and desire to secure by Letters Patent is:

1. A packing container for merchandising and storing photographic surfaces ready for immediate use in a camera, and also developing, if required, without removal therefrom or the use of a dark room, consisting of a destructible light proof receptacle formed of two separable members, said members being provided with devices for engaging means in a camera or holder for separating said members to expose a photographic surface within the same, and a destructible sealing means for holding said members in closed relation.

2. A packing container for merchandising and storing photographic surfaces ready for immediate use in a camera and also developing, if required, without removal therefrom, or the use of a dark room, consisting of a destructible light proof receptacle formed of two separable members, and provided with an aperture for the introduction of liquid into the same, said members being provided with exterior devices for engaging means in a camera or holder for separating such members to expose a photographic surface within the same, and a light proof closure for said aperture.

3. A packing container for merchandising and storing photographic surfaces ready for immediate use in a camera and also develop-

ing, if required, without removal therefrom, or the use of a dark room, consisting of a destructible light proof receptacle formed of two separable members and provided with an aperture for the introduction of liquid into the same, said members being provided with exterior devices for engaging means in a camera or holder for separating said members to expose a photographic surface within the same, and a destructible light proof sealing device for closing said aperture.

4. A packing container for merchandising and storing photographic surfaces ready for immediate use in a camera and also developing, if required, without removal therefrom, or the use of a dark room, consisting of a destructible light proof receptacle formed of two separable members, and provided with an aperture for introducing liquid into the container, and means for preventing the admission of light to the interior of the container through said aperture, said members being provided with devices for engaging means in a camera or holder for separating said members to expose a photographic surface within the same, and means for protecting a photographic surface within said container from accidental exposure while said members are separated.

5. As a new article of manufacture, a photographic package for merchandising, exposing and developing photographic surfaces without removal therefrom, or use of a dark room, comprising a destructible light proof receptacle formed of separable members, a plurality of photographic surfaces rigidly connected with separable portions of the container, and maintained at a distance from each other, and from all parts of the package to provide a space adjacent to each of said surfaces co-extensive therewith to permit the liquid introduced to freely pass over all portions of the photographic surfaces within the container, the members of the container being provided with devices for engaging means in the camera or holder to separate said members and expose the photographic surfaces within the same.

6. A packing container for merchandising and storing photographic surfaces ready for immediate use in the camera, and also developing, if required, without removal therefrom, or the use of a dark room, consisting of a destructible light proof receptacle formed of two separable members, said members being provided with devices for engaging means in a camera or holder for separating said members to expose a photographic surface within the same, a centrally located light proof partition separable from both of said members, and introduced between them, and a destructible sealing means for holding said separable members in closed relation.

7. A packing container for merchandising

- and storing photographic surfaces ready for immediate use in a camera, and also developing, if required, without removal therefrom, or the use of a dark room, consisting of a 5 destructible light proof receptacle formed of two separable members, said members being provided with devices for engaging means in a camera or holder for separating said members to expose a photographic surface 10 within the same, a centrally located light proof partition separable from both of said members, and introduced between them, said container being provided with an aperture for introducing liquid into the container, and means for preventing the admission of light through said aperture into the interior of the container. 15
8. A container for a photographic plate, comprising a light proof inclosing body consisting of separable members, means for hinging said members together on one edge, retaining straps secured to said members adjacent to an opposite edge of the container, and means for introducing a liquid into the 20 container.
9. A packing container for merchandising, exposing and developing photographic surfaces without removal therefrom, or use of a dark room, consisting of a destructible 25 light proof receptacle formed of two separable members, and a permanent holder for said container, provided with separable members, each of said members of the holder being provided with means for temporarily 30 securing it to a member of the container, and with a device for engaging means in a camera for separating the members of the holder and container simultaneously to expose a photographic surface within the 35 container. 40
10. In a photographic apparatus, the combination with a light proof container, comprising separable members having means for detachably connecting each of said members, of a holder for said container comprising a double flap body, both flaps of said body being provided with means for enabling either of them to be detachably engaged with actuating means for opening said holder, with retaining means for holding either of them in position during exposure and with means for detachably engaging them with the separable members of the inclosed container. 45
- 55 11. In a photographic apparatus, a light proof container for a photographic plate or plates, comprising separable members hinged together, and provided with means for the introduction of developing liquid, means for detachably engaging one of said members to hold it, and means movable with respect thereto for detachably engaging the other member to open the container and expose the plate therein. 60
- 65 12. In a photographic apparatus, the combination with a light proof container, comprising separable members, a retaining device for each of said members, and means for holding either one of said members, said container being provided with an aperture 70 for introducing liquid into the same, and means for preventing the admission of light through said aperture to the interior of the container and a longitudinally movable actuating rod for engaging the retaining device of the other member for opening said container. 75
13. In a photographic apparatus, the combination with a light proof container, comprising separable members, a retaining device for each of said members, means for holding either one of said members and a longitudinally movable actuating rod for engaging the retaining device of the other member for opening said container. 80
- 85 14. The combination with a container for a photographic plate, comprising a light proof inclosing body, provided with a movable portion for opening said body to expose the plate, said body being provided with an aperture for the introduction of liquid, and light proof means for temporarily closing said aperture, of a holder for said container, comprising a double flap body, both flaps of said body being provided with means for enabling either of them to be detachably engaged with actuating means for opening said holder, with retaining means for holding either of them in position during exposure and with means for detachably engaging them with the separable members of the inclosed container. 90
- 95 15. The combination with a container for a photographic plate, comprising a light proof inclosing body, provided with a movable portion for opening said body to expose the plate, said body being provided with an aperture for the introduction of liquid, and a destructible closure for said aperture, of a holder for said container, comprising a double flap body, both flaps of said body being provided with means for enabling either of them to be detachably engaged with actuating means for opening said holder, with retaining means for holding either of them in position during exposure and with means for detachably engaging them with the separable members of the inclosed container. 100
- 105 16. The combination with a container for a photographic plate, comprising a light proof inclosing body, provided with a movable portion for opening said body to expose the plate, said movable portion being provided with means for enabling it to be connected with actuating means for opening said container, of a holder for said container, comprising a double flap body, both flaps of said body being provided with means for enabling either of them to be detachably engaged with actuating means for 110
- 115 120
- 125
- 130

opening said holder, with retaining means for holding either of them in position during exposure and with means for detachably engaging them with the separable members of the inclosed container.

17. The combination with a container for a photographic plate, comprising a light proof inclosing body, provided with a movable portion for opening said body to expose 10 the plate, said movable portion being provided with means for enabling it to be connected with actuating means for opening said container, the other portion of the body being provided with retaining means for holding 15 it in position during exposure, of a holder for said container, comprising a double flap body, both flaps of said body being provided with means for enabling either of them to be detachably engaged with 20 actuating means for opening said holder, with retaining means for holding either of them in position during exposure and with means for detachably engaging them with the separable members of the inclosed container.

18. The combination with a container for photographic plate or plates comprising a light proof inclosing body, having separable portions for opening said body to expose 30 the plates and a centrally located light proof partition separable from both separable portions of the containers and introduced between them, of a holder for said container, comprising a double flap body, both flaps of 35 said body being provided with means for enabling either of them to be detachably engaged with actuating means for opening said holder, with retaining means for holding either of them in position during exposure 40 and with means for detachably engaging them with the separable members of the inclosed container.

19. The combination with a container for a photographic plate, comprising a light 45 proof inclosing body, having separable portions for opening said body to expose the plate, a centrally located light proof partition separate from both separable portions of the container and introduced between 50 them, said container being provided with an aperture for introducing a liquid into said container to develop the photographic plate or plates therein, and means for preventing the admission of light through said aperture to the interior of the container, of a holder for said container, comprising a double flap body, both flaps of said body being provided with means for enabling either 55 of them to be detachably engaged with actuating means for opening said holder, with 60

retaining means for holding either of them in position during exposure and with means for detachably engaging them with the separable members of the inclosed container.

20. The combination with a container for 65 a photographic plate, comprising a light proof inclosing body consisting of separable members, means for hinging said members together on one edge, retaining straps secured to said members adjacent to an opposite edge of the container, said container being provided with an aperture for introducing a liquid into the container, and means for preventing the admission of light through said aperture to the interior of the 75 container, of a holder for said container, comprising a double flap body, both flaps of said body being provided with means for enabling either of them to be detachably engaged with actuating means for opening 80 said holder, with retaining means for holding either of them in position during exposure and with means for detachably engaging them with the separable members of the inclosed container.

21. The combination with a container for photographic plates comprising a light proof inclosing body consisting of separable members, retaining straps secured to said members and a holder for said container 90 provided with securing devices for engaging said straps, said holder comprising a double flap body, both flaps of said body being provided with means for enabling either of them to be detachably engaged with actuating means for opening said holder, with retaining means for holding either of them in position during exposure and with means for detachably engaging them with the separable members of the inclosed container.

22. In a photographic apparatus, the combination with a light proof container, comprising separable members, a retaining device for each of said members, comprising a double flap body, both flaps of said body 105 being provided with means for enabling either of them to be detachably engaged with actuating means for opening said holder, with retaining means for holding either of them in position during exposure and with 110 means for detachably engaging them with the separable members of the inclosed container, means for holding either one of said flaps, and a longitudinally movable actuating rod for engaging the other flap for 115 opening said holder and container simultaneously.

In testimony whereof I affix my signature.

ERNEST HOWARD FARMER.
